INKING MECHANISM FOR PRINTING MACHINES

Original Filed Sept. 20, 1929 2 Sheets-Sheet 2

UNITED STATES PATENT OFFICE

HARRY V. BALL, OF CONCORD, MASSACHUSETTS, AND JOHN R. TOMLIN, OF BROOKLYN, NEW YORK, ASSIGNEES TO R. HOE & CO., INC., OF NEW YORK, N. Y., A CORPORATION OF NEW YORK

INKING MECHANISM FOR PRINTING MACHINES

Application filed September 20, 1929, Serial No. 393,973. Renewed November 18, 1931.

This invention relates to inking mechanism for rotary printing machines and more particularly to the distribution of ink on the ink cylinder, from which it is transferred to form rollers that deposit it on the printing plates.

It is the common practice to use ink rollers having a resilient moulded composition covering and support them in bearings so they run in contact with the ink cylinder. In order to distribute the ink evenly on the periphery of the cylinder, means are usually provided to move the rollers axially, or forward and back endwise with respect to the cylinder; the rollers so used being known as vibrating ink rollers.

The resilient quality of the rollers allows them to be set close enough to the cylinder so they will be flattened slightly when they press against the cylinder surface, but due to the curvature of the peripheries of the ink roller and the ink cylinder they are in engagement over an area of contact that is but little wider than a line and but a small portion of the surface of the roller is effective at any instant for distributing the ink on the cylinder. For this reason it is necessary to provide a large number of ink rollers and in many cases use an ink cylinder of larger diameter than it would otherwise be made, in order to provide the peripheral surface required for the rollers.

With the mechanism shown herein, the peripheral surface of the ink cylinder is used more effectively, for the means for distributing the ink is in contact with a relatively large area of the said surface at all times, and the distributing means is more efficient also, because a much larger area of its surface is effective at any instant than is the case when rollers are used.

It is an object of the invention to provide a means for distributing ink on an ink cylinder of a printing machine, that with relatively few parts and with an ink cylinder of relatively small diameter will distribute ink as effectively as an arrangement of rollers such as is used in common practice would, when used with a larger ink cylinder.

It is also an object of the invention to provide an ink distributing mechanism of gen-

erally improved construction, whereby the device will be simple, durable and inexpensive in construction, as well as convenient, practical, serviceable and efficient in its use.

With the foregoing and other objects in view, which will appear as the description proceeds, the invention resides in the combination and arrangement of parts, and in the details of construction hereinafter described and claimed, it being understood that various changes in the precise embodiment of the invention herein disclosed, may be made within the scope of what is claimed, without departing from the spirit of the invention.

In the accompanying drawings:

Figure 1 is a diagrammatic view of a portion of a rotary web printing machine as viewed from one side, showing the ink distributing belts that are a feature of the invention, and one form of mechanism for moving them forward and back lengthwise of the ink cylinder.

Figure 2 shows a fragment of one form of an ink distributing belt, partly in section;

Figure 3 shows a similar view of another form of ink distributing belt,

Figure 4 is a view of a portion of one of the ink belt rollers with the ink belt which it supports, shown in section;

Figure 5 is a view that is similar in many respects to Figure 1, but showing a modified form of mechanism for causing the ink belt to move forward and back lengthwise of the ink cylinder;

Figure 6 is an irregular fragmentary view partly in section showing a portion of the ink cylinder and adjacent parts as seen on the broken line A—A of Figure 5; and

Figure 7 is a diagrammatic plan view of the arrangement shown in Figures 5 and 6 showing how the ink belt is skewed with respect to the ink cylinder.

Referring to the drawings, 11 indicates one of the two side frames of a rotary printing machine. Suitable bearings are carried by the frames and support an impression cylinder 12, and a form cylinder 13, which are suitably driven and geared to run at the same speed.

Ink is supplied from a reservoir not shown

and conducted through pipes 14, to an ink rail 15, from which it is discharged against the periphery of the revolving ink cylinder 16. Details of an ink supply system of this type is shown in Halliwell Patent Number 1,644,723 dated October 11, 1927, hence further description is unnecessary.

An ink belt 17, is supported on ink belt rollers 18 and 19, and a similar ink belt 21, is supported on ink belt rollers 22 and 23. The rollers are mounted in bearings arranged to hold the belts in engagement with the cylinder 16, and they are driven thereby. A fragment of one form of ink belt is shown in Figure 2, and a fragment of another form of ink belt is shown in Figure 3. The belts may be made of rubber vulcanized on canvas, or other suitable material, and are preferably formed with continuous ribs as shown at 24 in Figure 2, or mutilated ribs as shown at 25 in Figure 3, the latter arrangement producing a more flexible belt. The function of these ribs is to engage grooves 26, formed in the ink belt rollers in the manner shown in Figure 4, and insure that the proper relation between the belts and the rollers is maintained.

In the preferred arrangement, the ink rollers and the belts carried thereby are vibrated, or moved, parallel to the axis of the rollers to distribute the ink on the cylinder 16. This is accomplished by a well known arrangement comprising vibrator arms 27, having rollers 28, which engage with grooved collars secured to the ink belt roller shafts.

The vibrator arms are secured to a shaft 29, rotatably supported in brackets 31, secured to the frame 11. A driving arm 32 is also secured to the shaft 29 and carries a roller 33, which engages a grooved cam 34, mounted concentric with the cylinder 16 and driven preferably at a slower speed by gearing not shown.

Means are thus provided for moving the rollers 22 and 23 axially, and as the ribs of the ink belt are in engagement with the grooves in the ink belt rollers, the belt is moved lengthwise along the surface of the cylinder 16 while running in contact with it, and thus acts to distribute the ink on the surface thereof. Those to whom this form of ink roller vibrating mechanism is unknown, can find it fully disclosed in Schmidt Patent No. 1,822,829 dated November 25, 1919.

Means similar to that described above is provided for vibrating the belt 17, which is carried by the rollers 18 and 19, and is shown in dotted lines in Figure 1.

An ink roller 35, assists in distributing the ink on the cylinder, and other rollers 35, 36, 37 and 38 act to transfer the ink from the cylinder 16 to the printing form carried on the cylinder 13.

A gear train is provided to drive the cylinder 16 and the vibrating mechanism in timed

relation to the printing cylinder, the pitch lines of the gears being indicated at 39, 41, 42, 43 and 44.

In the modified form of the invention shown in Figures 5, 6, and 7, the ink belt rollers instead of being forcibly moved axially, are skewed alternately in opposite directions with respect to the cylinder 16' and the ink belt is thus drawn back and forth lengthwise of the cylinder.

Parts that are common to both forms of the invention are marked prime ('') in the drawings showing the modified form.

The mechanism for skewing the ink belt rollers includes a pair of frames 51 and 52. A bracket 53 is secured to the side frame 11' and is formed with a tubular portion 54 through which the shaft 16'' of the cylinder 16' passes. The outside of the tubular portion is turned to form a bearing for the hub 55 of the frame 52. The outside of the hub 55 is likewise turned to form a bearing for the hub 56 of the frame 51. The frames 51 and 52 may thus be rocked about the axis of the cylinder 16'.

Bearings for the shafts of the ink belt rollers are provided in the frames 51 and 52 at 57, 58, 59 and 61. These bearings may be of any self-aligning type that will permit the oscillating motion of the roller shafts with respect to the frames, that is incident to skewing the rollers relatively to the ink cylinders.

The required rocking motion is imparted to the frames 51 and 52 by levers 62 and 63, fulcrumed respectively on studs 64 and 65, secured to the frame 11. These levers are operated by a cam 66, which rotates on the shaft 16'' and has the gear 67 secured to it. Means such as that shown in Schmidt patent referred to above, or other suitable mechanism may be provided to rotate the cam 66, preferably at a speed considerably slower than the speed of the cylinder 16'.

It will be understood that a similar arrangement of frames, levers and a cam is provided at the opposite side of the machine, and that the cams are driven at the same speed, and are positioned in opposite relation to each other, thus causing the frames on one side of the machine to be in a forward position with respect to the rotation of the cylinder, while the frames on the other side are in a backward position, as shown in Figure 7.

When the ink belt is in the position shown in full lines in Figure 7, it is evident that it will move toward one side as the cylinder is rotated, and when the cams have turned the arms so the belt is in the position shown by the dotted lines it will move toward the opposite side.

Causing the belt to thus traverse back and forth across the cylinder results in evenly distributing the ink thereon.

What we claim is:

1. In an inking mechanism for a printing machine, an ink cylinder, a belt running in contact with the cylinder and wrapped around a portion of its periphery, and means for vibrating the belt lengthwise of the cylinder.
2. In an inking mechanism for a printing machine, an ink cylinder, a belt in contact with an arc of the periphery of the cylinder, rollers supporting the belt and means for vibrating the belt lengthwise with respect to the cylinder.
3. In an inking mechanism for a printing machine, an ink cylinder, a belt in contact with an arc of the periphery of the cylinder, rollers supporting the belt, a groove in one of the rollers co-acting with the belt to prevent lateral motion of the belt on the roller and means for vibrating the belt lengthwise of the cylinder.
4. In an inking mechanism for a printing machine, an ink cylinder, a belt in contact with an arc of the periphery of the cylinder, rollers supporting the belt, grooves in the rollers, means on the belt co-acting with the grooves to prevent lateral movement of the belt relative to the rollers, and means for vibrating the belt lengthwise of the cylinder.
5. In an inking mechanism for a printing machine, an ink cylinder, a belt in contact with an arc of the periphery of the cylinder, rollers supporting the belt, grooves in the rollers, a rib on the belt co-acting with the grooves, and means for vibrating the belt lengthwise of the cylinder.
6. In an inking mechanism for a printing machine, an ink cylinder, a belt running in contact with an arc of the periphery of the cylinder, rollers supporting the belt, and means acting on the rollers whereby the belt is caused to move toward each end of the cylinder alternately.
7. In an inking mechanism for a printing machine, an ink cylinder, a belt, rollers holding the belt in contact with an arc of the periphery of the cylinder, journals for the rollers, bearings for the journals, and means for causing the journals to move axially in the bearings.
8. In an inking mechanism for a printing machine, an ink cylinder, a belt, rollers to hold the belt in running engagement with an arc of the cylinder; said rollers being supported with their axes parallel with each other but out of parallelism with the axis of the cylinder, and means for moving the axes of the rollers while keeping them parallel with each other and keeping the belt in engagement with the cylinder, whereby the belt will be made to run toward one end of the cylinder and then toward the other end.
9. In an inking mechanism for a printing machine, an ink cylinder, a belt in contact with an arc of the periphery of the cylinder,

rollers supporting the belt, grooves in the rollers, a mutilated rib on the belt co-acting with the grooves, and means for vibrating the belt lengthwise of the cylinder.

10. In an inking mechanism for a printing machine, an ink cylinder, a belt in operating engagement with an arc of the periphery of the cylinder, grooved rollers supporting the belt, a plurality of ribs on the belt engaging the grooves in the rollers, and means acting on the rollers whereby the belt is caused to move lengthwise along the circumferential surface of the cylinder.

In testimony whereof, we affix our signatures.

HARRY V. BALL.
JOHN R. TOMLIN.
